UNITED STATES PATENT OFFICE.

WILLIAM G. COUGHLIN, OF PHILADELPHIA, PENNSYLVANIA.

RAILWAY CONSTRUCTION.

Application filed August 14, 1918. Serial No. 249,882.

To all whom it may concern:

Be it known that I, WILLIAM G. COUGHLIN, a citizen of the United States, and residing at Philadelphia, Philadelphia County, 5 State of Pennsylvania, have invented certain new and useful Improvements in Railway Constructors, of which the following is a specification.

The present invention relates to rail 10 chairs and ties for supporting the rails in railway constructions.

The principal objects of the invention are to provide a rail chair which has a maximum rigidity or stiffness for the amount of 15 material used; to provide a chair having a substantially uninterrupted bearing on its support throughout its area; to provide a form of fastening means to secure the chair to the support which does not mutilate or 20 weaken the support; to provide means for regauging the rails without moving the rail chairs; to provide means for securing the rails in position which permits rails having different width flanges to be used; to provide 25 an exceedingly strong and dependable means to secure the rail to the chair; to provide independent supports for the pair of rails of the track in combination with means to adjustably space the supports; to provide 30 such spacing means directly connecting opposite chairs; to provide a cross-tie of approximately the same section and dimensions as the usual tie and constructed or built up of timber, concrete, or other mate- 35 rial; to provide built up cross-ties made from timber heretofore considered unsuitable for the purpose; and to provide a short tie or bearing block of wood, concrete or other material, or even from sound sections 40 cut from discarded wooden ties in combination with means to hold the bearing blocks in proper spaced relation. Other objects and features of novelty will be apparent from the description taken in connection 45 with the drawings in which:

Figure 1 is a top plan view of a rail chair constructed in accordance with the present invention;

Figure 2 is a side elevation of the same;

50 Figure 3 is a side elevation of a chair mounted on a support and showing the manner of securing the rail thereto and the chair to the support;

Figure 4 is a perspective view of a clip 55 employed for the purpose of securing the rail to the chair;

Figure 5 is a top plan view of a built-up cross tie having a pair of the present rail chairs secured thereto;

Figure 6 is a side elevation of the parts 60 shown in Figure 5 the rails being shown in cross section;

Figure 7 is a sectional elevation taken substantially on the line 7—7 of Figure 6;

Figure 8 is a sectional elevation similar 65 to Figure 7 and illustrating a modified form of chair which is divided transversely of the rail to accommodate the chair to ties of different widths;

Figure 9 is a side elevation of a pair of 70 independent supports having the present rail chairs mounted thereon, the chairs being maintained in proper spaced relation by a tie rod connecting the same;

Figure 20 is a sectional elevation taken substantially on the line 20—20 of Figure 19;

Figure 21 is a top plan view of a construction in which the rail chairs are di-

vided transversely of the rail and the corresponding parts of opposite chairs connected by an integral tie rod, the chairs being mounted on independent supports;

5 Figure 22 is a side elevation of a construction in which the chairs are mounted on independent supports and the rails are held in proper spaced relation by a tie rod connecting the rails;

10 Figure 23 is an elevation showing a modified form of bolt for securing the rail to the plate of the chair.

Referring to the drawings and more particularly to Figures 1 to 3 inclusive, the reference character 30 indicates a plate which forms the main member of the rail chair. This plate is adapted to be positioned so that its underside has a bearing throughout its area on the support, there being no perforations in the plate so that the bearing area is a maximum. As shown this plate is substantially rectangular in outline and at a pair of lateral edges has the depending stiffening flanges 31 provided for the purpose of reinforcing the plate against bending when it is subjected to the load of a train passing over the same. These flanges are preferably trapezoidal in outline, as shown in Figure 2, although it is obvious that the invention is not limited to such an outline. The lower edges of the flanges 31 may be provided with flanges 32 which act to stiffen and reinforce the depending flanges 31. The opposite lateral edges of the plate 31 previously mentioned also have the laterally projecting wings 33. As shown in Figure 1 there are a pair of these wings spaced apart at each of the said edges and the sides of the wings facing each other may be formed with notches 34 for a purpose presently to be described. As shown in Figure 7 the chair is designed to be mounted on a support astraddle of the same, the flanges 31 being in contact with the sides of the support or tie. For the purpose of securing the chair to a support without injuring or weakening the support or tie, bolts 35 extends through the support and aligned holes 36 formed in the flanges 31. In order that the support or tie may not be weakened these transverse bolts are preferably positioned so that they are at the neutral axis of the same. If the chair is used in connection with a concrete or similar type of support the flanges 31 may be cut to form tongues 37 which are adapted to be bent up at right angles to the flanges so that they will extend into the support and furnish a further means for securing the chair to a support.

In order to secure the rail to the plate 30 of the chair, clips 38 are employed. As clearly shown in Figure 4 these clips have a laterally projecting flange 39 at the top 65 thereof the under surface body of which is

inclined so that it will have a bearing on the upper side of the flange at the base of the rail. The clip is also formed with a substantially rectangular projection 41 on the bottom which is designed to be positioned in one of the notches 34, the parts being arranged so that the clip will be held up against the rail by the engagement of the projection 41 in the notch 34. The clip is also formed with a vertically extending bolt hole 42 for a bolt 43 the head 44 of which is provided with a circular aperture for the bolt 35. The upper end of the bolt projects above the clip and has a nut 45 threaded thereon there being a washer 46 between the nut and the top of the clip. In the form of the invention now being described there are four clips and four bolts 43, two being arranged on each side of the base flange of the rail. It will be seen that this construction provides a means for securing the rail to the chair without perforating the plate 30 of the chair, this desirable feature following from the fact that the bolts or securing means are disposed laterally of the edges of the plate 30.

In some of the forms of the invention described hereinafter it is desirable to provide means for adjusting the rail transversely with respect to the chair for the purpose of regauging the rails. This may be accomplished by forming the clips 38 with projections 41 of different sizes. Thus as shown in Figure 3 it will be observed that the left hand clip has a projection of greater width than the right hand clip. Consequently, if a clip is substituted for the left hand one which has a narrower projection 41 and a clip is substituted for the right hand one with a wider projection 41, the rail will be shifted slightly to the left of the position shown in said figure. This condition also permits rails having flanges of different widths to be secured to the chair. In other words, a rail having a narrow base flange, or a rail having a wide flange may be secured to a chair, it only being necessary to select the proper clips.

In addition to providing a chair which has substantially an imperforate bearing plate, it will be observed that the means for securing the rail to the chair does not act directly between the rail and chair but rather between the rail and the support. Consequently, the forces which may act to 115 tend to move the rail upwardly are transmitted directly to the support, which, of course, is better than having the forces act through the chair. It follows from this construction that there is a less tendency 120 for the chair to be pulled away from the support than in the fastenings heretofore employed.

In Figures 5 to 7 inclusive I have illustrated a pair of chairs mounted on a built- 125

up cross tie. As shown the tie comprises a vertically arranged plank or board 47 which extends transversely under both of the rails. At each end of this board and under the rails 5 shorter planks or boards 48 are secured to the opposite sides of the central plank 47, being fastened thereto in any suitable manner as by means of the bolts 49. It will be observed that this tie employs lumber which 10 heretofore has been considered unsuitable for tie construction. Furthermore, the wider built-up ends of the tie form bearings or foundation blocks, furnishing all the support needed, it being a well known fact that 15 it is undesirable to have the middle portion of the tie have a solid bearing for the reason that such solid bearing produces a condition known as "tie-bound," which causes the train to roll. Further, it is quite 20 practicable, particularly in the case of concrete as described hereinafter, to furnish as much bearing area on the roadbed in a short tie by increasing its width as is now secured by a full length tie with the further advantage 25 of providing this bearing area under the rail and not in the center of the track, thus avoiding the "tie-bound" condition.

As illustrated in the said Figures 5 and 7 inclusive the right hand chair is of the form 30 already described, that is to say the rail is mounted on a chair so that it can be adjusted transversely, the chair being nonadjustably secured to the tie. As the right hand rail, therefore, is transversely adjustable the left hand rail, if desired, may be secured to the chair in a nonadjustable manner and the left hand chair of Figures 5 and 6 is 35 designed for this purpose. Thus the plate 30 at one side of the rail has the vertically disposed flanges 50 which are formed with the notches 51 at the edges facing the rail flange, these notches being designed to receive the said rail flange. The opposite side 40 of the rail flange may be secured to the chair by clips 38 in the manner previously described.

If it is desired to have a chair which will fit ties of different widths then the chairs 50 already described may be divided longitudinally as shown in Figure 8. Thus the plate previously described consists of two plates 30', the remaining parts of the chair being as already described.

In Figures 9, 10 and 11, I have illustrated 55 another construction in which the rail chairs are mounted on independent supports which as shown are concrete. As already mentioned, it is practicable to increase the bearing area of the supports lengthwise of the 60 rails as compared to the present practice. In this case, however, the supports 51' should be made with sloping sides as shown in Figure 10 so as to afford sufficient space for the tamping of the ties. These inclined 65 sides provide a construction with a further

advantage that the load of the rail and train are carried substantially at the middle third of the width of the support. In the form of the invention shown in these figures the left hand chair is of substantially the 70 same construction as the corresponding chair shown in Figure 5 except that the inside edge of the plate 30 is provided with the upstanding lug 52. The right hand chair is like the right hand chair of Figure 75 5 except that on the inside edge of the plate 30 is formed a lug 53 facing the lug 52. A tie rod 54 has end lugs 55 which are connected to the lugs 52 and 53 by bolts 56. Thus the rail chairs are held in proper 80 spaced relation and the regauging of the track is provided for by securing the right hand rail adjustably to the chair. If it is desired to insulate one rail from the other then insulating washers 57 may be interposed 85 between the lugs 52 and 55 and between the bolt 56 and the said lugs. Figure 10 clearly shows how the tongues 37 struck up from the side flanges 31 may be embedded in the concrete. Figure 11 in addition to showing a 90 plan view of the right hand chair of Figure 9, also clearly illustrates how the rail is secured for regauging. Thus it will be seen that the distance *a* between the left hand edge of the base of the rail and the adjacent 95 notch in the wing 33 is greater than the corresponding distance *b* at the right hand side of the rail, the rail being held in this position because the projection 41 on the bottom of the left hand clip 38 is wider than the one on the right hand clip. Consequently, if the two clips on the left side of the rail are interchanged with the two clips on the right hand side the rail will be moved 100 slightly to the left as viewed in this figure. 105 If it is desired to cushion the chair a block 58 of wood or other cushioning material may be interposed between the top surface of the support 51' and the underside of the plate 30, and may be secured against displacement 110 as by means of screws 59 extending through the plate 30 into the cushion member. As shown in Figure 9, if it is desired to incline the rail slightly with respect to the vertical 115 then these cushioning members may be made slightly wedge shaped.

In Figures 12 to 14 inclusive the construction shown includes a reinforced concrete cross tie 60 extending transversely under both rails of the railroad. A pair of rail 120 chairs similar to the ones described and shown in Figure 9 are mounted on this tie, the opposite lateral edges of which are inclined with respect to the vertical. The tie is reinforced by a member 61 embedded 125 therein and extending longitudinally. This reinforcing member is cut away at its central portion so that at its ends it is of greater height than at said central portion. The intermediate portion is provided with a hori- 130

zontal flange 62 at its upper edge and the 5 end portions have the horizontal flanges 63 at their lower edges. It will be noted that the bolts 35 which secure the chairs to the tie extend through the end portions of the reinforcing member 61 and consequently this member acts as a means for holding the chairs in proper spaced relation. If it is desired to regauge the track then the clips 10 of the right hand chair may be interchanged in the manner previously described. Cushioning blocks 58 may be interposed between the chairs and the top of the tie as described in connection with Figure 9.

15 Figures 15 to 17 illustrate a further modification. In this form of the invention the plate 130 of the chairs has a depending flange 131 at one lateral edge only and this flange extends downwardly and is embedded in 20 the tie 64, a lower edge thereof having the horizontal flange 132. The right hand chair has the lateral wings 133 at the edge having the depending flange and the rail is secured to this chair by clips 38 and the bolts 43. 25 These bolts 43 are secured to the tie 64 by the transverse bolts 35 which extend through the flange 131 of the chair and are positioned at the neutral axis of the tie. The left hand chair also has a depending flange 30 131 at the same edge as the right hand chair and the plate 130 is provided at one of its lateral edges, that is, at the one having the depending flange, with the vertical flange 50 having a notch 51 receiving the flange at 35 the base of the rail and also with a wing 133 for a clip 38 secured in the manner already fully described. As shown, the two depending flanges 131 are integrally connected by the reinforcing bar 65 and consequently the 40 chairs are maintained rigidly in proper spaced relation. It will be observed that the manner of securing the right hand rail to its chair provides means for regauging the track. If desired cushioning blocks 58 may 45 be interposed between the bottom of the chair and the tie.

50 In the construction illustrated in Figures 18, 19 and 20, chairs of somewhat different form from the ones previously described are mounted on independent supports 66 which as shown are made of concrete. Each of the chairs comprises the flat plate 30 at one lateral edge having the depending reinforcing flange 231, the flange being stiffened by 55 a projecting rib 232 at its edges. The chairs are designed to be disposed on the supports with the said reinforcing flange 231 embedded in the concrete. At one of its lateral edges the plate 30 has the vertical flange 50 formed with a notch 51 adapted to fit over 60 the flange at the base of the rail. The opposite lateral edge of the plate has a similar flange 50 which is disposed diagonally with respect to the first flange, this latter flange 65 also being formed with a notch 51 positioned

to fit over the opposite edge of the base flange of the rail. If desired, cushioning blocks 58 may be arranged between the top of the support and the bottom of the plate 30 and held against displacement by the 70 screws 59. In order to secure this form of the chair to the rail, the chair is placed under the rail and inclined thereto and is thereafter swung in a horizontal plane to a position substantially at right angles to the rail. 75 This will cause the flanges 50 to move so that the base flange of the rail will be received in the notches 51. It will be observed that no provision is made in the means for securing the chair to the rail for adjusting the rails 80 transversely with respect to each other. In order to provide for such adjustment and also hold the rails in proper spaced relation tie rods 67 are provided, these rods having the bent ends 68 slightly inclined to the 85 length of the rod and formed with the series of holes 69 for the bolts 35 which extend through the support and the reinforcing flanges 231 of the chairs. Preferably one of these tie rods is disposed on each side of the 90 supports and it will be seen, if it is desired to change the gauge of the track, that a very fine adjustment may be obtained by passing the bolts 35 through one of the other holes 69 formed in the tie rods. Furthermore as 95 the bolts 35 pass through the reinforcing flanges 231, the chairs are in effect directly connected by the said tie rods, that is to say, the stresses which act to cause the spacing of the rails to change are carried directly 100 from the chairs to the tie rods, the supports merely performing the function of carrying the rails and affording sufficient bearing area on the roadbed.

105 It will be observed that the flanges 50 which are at the upper edges of the plates 30 as shown in Figure 18 are positioned on the inside of the rails while the other flanges 50 are positioned on the outside of the rails. This arrangement of the flanges is important in order that the tie rod 67 may prevent 110 swinging of the supports or chairs in a direction which might disengage the notches from the base flanges of the rails.

115 In Figure 21 I have illustrated a form of the invention in which the chairs are constructed so that they may be fitted over supports of different widths. As shown the left hand chair is similar to the left hand chair of Figure 5 except that it is divided longitudinally, the plate thus comprising the two parts 330 and 331, the rail being non-adjustably secured to the chair. The opposite right hand chair is similar to the right hand chair of Figure 5 except that the plate 120 is divided longitudinally, that is, transversely to the rail, thus consisting of the two parts 330' and 331'. For the purpose of holding the rails in proper gauge the plates 330 and 330' are connected by the 125 130

integral tie rod 354 and the plates 331 and 331' are connected by the parallel and similar integral tie rod 355. As shown, the chairs are mounted on independent concrete supports 351 and cushioning blocks 58 may be disposed between the bottom of the chair plates and the top of the support. The rails may be re-gauged by interchanging the clips 38 of the right hand chair in the manner 10 previously described. Figure 22 illustrates a construction similar to Figures 9, 10 and 11 except that the chairs are not provided with the lugs 52 and 53, the rails being held in proper gauged position by a tie rod 454 having threaded ends 455 directly connected to the webs of the rails by the nuts 456 mounted on the opposite sides of the said webs. When it is necessary to re-gauge the 15 track the clips 38 of the right hand chair 20 are interchanged and the nuts 456 on the tie rod turned so that the rails are held in the gauged relation.

In Figure 23 a modified construction is shown for clamping the clips 38 against the 25 base flange of the rails. Thus instead of using a bolt which extends through the clip and has its head mounted on the transverse bolts 35, a shorter bolt 43' is employed having a head 143 which abuts the under 30 surface of the wings 33. By screwing down the nut 45 the clip 38 will be drawn down on to the base flange of the rail, upward motion being prevented by the head 143 engaging the undersurface of said wing 33.

35 It will be observed, in all forms of the invention described, the plate of the chair projects on each side of the rail, so that the base of the rail does not bear on more than the middle third of the plate. Thus, tilting 40 of the plate on the tie is resisted, so that the edges parallel to the rail do not dig into the tie. Furthermore, because of the reinforcing flanges, a plate of relatively great length transverse to the rail may be employed without making it unduly heavy.

Although several forms of the invention have been described in detail it is understood that the invention is not thus limited but includes all changes and modifications which 50 come within the scope of the appended claims.

Having thus described the invention what is claimed as new and desired to be secured by Letters Patent is:—

55 1. A rail comprising a flat plate adapted to be mounted on a support with its lower surface in uninterrupted contact with the support throughout the width of the support and the length of the plate, said plate having an integral depending reinforcing flange to stiffen the same extending substantially from end to end of the plate and transversely to the rail, means to secure the rail to the plate without perforating the latter, the 60 plate extending under and projecting a sub-

stantial amount at both sides of the rail, and means to secure the flange to the support whereby the rail is held against displacement relative to the support without perforating the plate. 70

2. In combination, a support, a rail chair comprising a flat plate adapted to be mounted on the support with its lower surface in contact therewith throughout an area equal to the width of the support and the length 75 of the plate, said plate projecting a substantial amount at both sides of the rail and having an integral depending reinforcing flange to stiffen the same extending substantially from end to end of the plate and transversely to the rail, means arranged laterally 80 of the plate cooperating therewith to secure the rail to the plate, and means to secure said flange to the support whereby the chair is held against movement relative to the support and the rail relative to the chair without perforating the plate. 85

3. In combination, a support, a rail chair comprising a flat plate adapted to be mounted on said support, said plate projecting at 90 both sides of the rail an amount at least substantially equal to the width of the rail and having an integral depending reinforcing flange to stiffen the same in the direction transversely of the rail, a bolt extending 95 through said flange and support, and means disposed outside the area of the plate resting on the support to secure the rail to the plate including a member operatively connected to the base of the rail and said bolt. 100

4. In combination, a support, a rail chair comprising a flat plate adapted to be mounted on said support, said plate projecting at both sides of the rail an amount at least substantially equal to the width of the rail and having an integral depending reinforcing flange to stiffen the same in the direction transversely of the rail, a bolt extending 105 through said flange and support, and means to secure the rail to the plate including a member operatively connected to the base of the rail and said bolt and disposed laterally 110 of the plate whereby the chair is held against movement relative to the support and the rail relative to the chair without perforating the plate. 115

5. In combination, a support, a rail chair comprising a flat plate adapted to be mounted on said support, said plate having an integral depending reinforcing flange to stiffen 120 the same in the direction transversely of the rail, a pair of parallel bolts extending through said flange and support, and means to secure the rail to the plate including a bolt at each side of the rail operatively connected to the base of the rail and one of said pair of bolts. 125

6. The combination with a support, of a rail chair comprising a flat plate of a length sufficient to project from each side of the 130

rail a substantial amount, the lower surface of said plate resting on said support substantially throughout its area, means disposed laterally outside said area to secure 5 the rail and chair together, and means reinforcing the plate against bending including a flange extending substantially from end to end of the plate transversely of the rail, said flange being deepest at the middle section 10 thereof and tapered in depth from said section to the respective ends of the plate.

7. The combination with a support, of a rail chair comprising a flat plate of a length sufficient to project from each side of the 15 rail a substantial amount, the lower surface of said plate resting on said support substantially throughout its area, means disposed laterally outside said area to secure the rail and chair together, and means reinforcing the plate against bending including a flange extending substantially from end to end of the plate transversely of the rail, said flange being deepest at the middle section 20 thereof and tapered in depth from said section to the respective ends of the plate, said flange having a stiffening flange at its marginal edge.

8. In combination, a support, a rail chair comprising a flat plate adapted to be mounted on the support, a bolt extending through the support arranged parallel to said plate, means to hold the rail to the plate and the chair against movement relative to the support including a second bolt having one end 30 connected to the first mentioned bolt, and a clip on the other end clamped against the flange at the base of the rail, and means to hold the rail against lateral movement relative to the chair.

40 9. In combination, a support, a rail chair comprising a flat plate adapted to be mounted on the support, a bolt extending through the support arranged parallel to said plate, means to hold the rail to the plate and the 45 chair against movement relative to the support including a second bolt having one end connected to the first mentioned bolt, and a clip on the other end clamped against the flange at the base of the rail, and means carried by the plate to hold the rail against lateral movement relative to the chair.

55 10. In combination, a support, a rail chair comprising a flat plate bearing on the support and projecting on each side of the rail an amount at least substantially equal to the width of the rail, said plate having a depending reinforcing flange at each of a pair of its edges transverse to the rail, said flanges being disposed to contact with 60 the sides of the support, a bolt passing through the support and said flanges, and means arranged laterally outside of the area of the plate bearing on the support to secure the rail to the chair.

65 11. In combination, a support, a rail chair

comprising a flat plate bearing on said support and projecting at each side of the rail an amount at least substantially equal to the width of the rail, said plate having a depending reinforcing flange transverse to the rail, a bolt passing through the flange and support, a second bolt having one end connected to the first mentioned bolt and a clip on the other end clamped against the flange at the base of the rail. 75

12. In combination, a support, a rail chair comprising a flat plate having a depending reinforcing flange transverse to the rail, a bolt passing through the flange and support, means to secure the rail to the chair 80 including a clip bearing on the flange at the base of the rail and a bolt disposed laterally of the plate to clamp the said rail flange between the clip and plate.

13. In combination, a support, a rail chair 85 comprising a flat plate projecting on both sides of the rail an amount at least substantially equal to the width of the rail and having a depending reinforcing flange at each of a pair of its edges transverse to the rail, said flanges being disposed to contact with the sides of the support, means to secure the chair to the support and means disposed laterally of the plate and said flanges to secure the rail to the chair. 90

14. As an article of manufacture, a rail chair comprising a flat plate having a perpendicularly disposed stiffening flange at each of its longitudinal edges, and a pair of wings substantially in the same plane with the plate projecting laterally from each of said edges, the wings of each pair being spaced a distance greater than the width of the base of the rail. 100

15. In combination, a support, a rail chair 105 comprising a plate mounted on said support and having lateral wings in substantially the same plane as the plate, a portion of each wing being cut away to form a notch, and means to secure the rail and chair against movement relative to the support including a bolt extending through said notch having one end connected to the support and the other end operative to clamp the flange of the rail base against the 110 plate. 115

16. In combination, a support, a rail chair comprising a plate mounted on said support and having lateral wings in substantially the same plane as the plate, a portion 120 of each wing being cut away to form a notch, and means to secure the rail and chair against movement relative to the support including a clip bearing on the flange of the rail base and a bolt extending through said clip and notch and having its lower end connected to the support. 125

17. In combination, a support, a rail chair comprising a plate mounted on said support and having lateral wings in substan- 130

tially the same plane as the plate, a portion of each wing being cut away to form a notch, and means to secure the rail and chair against movement relative to the support 5 including a clip bearing on the flange of the rail base having a portion fitting in said notch, and a bolt extending through said clip and connected at its lower end to the support.

10 18. In combination, a support, a rail chair comprising a plate adapted to be mounted on the support, said plate having a depending reinforcing flange extending transversely of the rail and a lateral wing substantially in the plane of the plate, said wing having a portion cut away to form a notch, means to secure the chair to the support, and means to secure the rail to the chair, including a clip bearing on the flange 15 at the base of the rail having a portion fitted in said notch and a bolt to clamp the clip against the rail flange.

19. In combination, a support, a rail chair comprising a plate adapted to be mounted 20 on the support, said plate having a depending reinforcing flange extending transversely of the rail and a lateral wing substantially in the plane of the plate, said wing having a portion cut away to form a 25 notch, means to secure the chair to the support including a bolt passing through said flange and support, and means to secure the rail to the chair including a clip bearing on the flange at the base of the rail having a 30 portion fitted in said notch and a bolt hav- 35

ing its lower end connected to the first mentioned bolt to clamp the clip against the rail flange.

20. The combination with a cross tie of a U shaped chair astraddle said tie over an area equal to the width of the tie and the length of the plate having a plate bearing on the tie and projecting on each side of the rail an amount such that the rail rests on the middle third of the plate and a bolt 40 passing through the flanges of the chair, and the neutral axis of the tie to secure the parts together. 45

21. In combination, a support, a rail chair comprising a plate mounted on said support and having lateral wings in substantially the same plane as the plate, and means to secure the rail and chair against movement relative to the support including a bolt extending past an end of a wing having one end connected to the support and the other end operative to clamp the flange 50 of the rail base against the plate. 55

22. As an article of manufacture, a rail chair comprising a flat plate having a perpendicularly disposed stiffening flange and a pair of wings substantially in the same plane with the plate projecting laterally from each of its longitudinal edges, the wings of each pair being spaced a distance 60 greater than the width of the base of the rail. 65

In testimony whereof I affix my signature.

WILLIAM G. COUGHLIN.

Certificate of Correction.

It is hereby certified that in Letters Patent No. 1,441,401, granted January 9, 1923, upon the application of William G. Coughlin, of Philadelphia, Pennsylvania, for an improvement in "Railway Constructions," an error appears in the printed specification requiring correction as follows: Page 5, line 55, claim 1, after the word "rail" insert the word *chair*; and that the said Letters Patent should be read with this correction therein that the same may conform to the record of the case in the Patent Office.

Signed and sealed this 6th day of February, A. D., 1923.

[**SEAL.**]

KARL FENNING,

Acting Commissioner of Patents.
